Primary Examiner—Brian N. Vinson*(74) Attorney, Agent, or Firm*—Harness, Dickey & Pierce, P.L.C.(57) **CLAIM**

The ornamental design for a circular saw handle, as shown and described.

DESCRIPTION

FIG. 1 is a front perspective view of a circular saw handle; FIG. 2 is a rear perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The broken line showings in the above figures are for illustrative purposes only and do not form part of the claimed design.
